CONDENSER CIRCULATING SYSTEM

Frank D. Shumate, Larchmont, N. Y., and George W. Saathoff, South Orange, N. J.; said Shumate assignor to Worthington Pump and Machinery Corporation, Harrison, N. J., a corporation of Delaware; said Saathoff assignor to Helen S. Davis, Lexington, Mass.

Application July 23, 1942, Serial No. 452,010

12 Claims. (Cl. 257—44)

1

This invention relates to power plants or systems, and more particularly to cooling water circulating systems for surface steam condensers, heat transfer or cooling devices employed therein.

Such power plants are often located upon rivers and are dependent thereon for their supply of cooling water. The water level of such rivers varies widely with the seasons and is further affected by rainfall. Or, the power plant may be located at some height above the water level of the source of supply of cooling water, as upon a bluff adjacent a river or lake. In such locations, the system of the present invention is particularly desirable and adaptable.

Patents No. 1,769,671, issued July 1, 1930, and 1,762,115, issued June 3, 1930, refer to installations of this character, such as those installations in the Ohio River Valley, and describe the conditions met therein. The invention of these prior patents deals with the provision of economical circulation of cooling water in power plants of this type.

The present invention provides, in a system of this kind, a primary motor driven pump and a secondary or booster pump driven by a hydraulic turbine, the latter being operated by the return or discharging circulating cooling water of the condenser system, thus permitting both the primary and secondary pumps to be designed with characteristics required for most efficient and practical performance of their respective duties, increasing the over-all efficiency and economy of the system.

An object of the present invention is to provide, in a circulating cooling water system for steam condensers in a power plant of the class above referred to, means of varying the static head on the hydraulic turbine utilizing the cooling water, after discharge from the condenser, as its motivating power.

Control of the static head on the hydraulic turbine is provided by means of a penstock or control well between the circulating water outlet of the condenser and the inlet of the hydraulic turbine, together with means for varying the water level in such penstock or control well through a wide range.

Control of the static head on the turbine permits the hydraulic turbine driven pump to be operated at its most efficient point in relation to the total dynamic head thereon, the total dynamic head on the motor driven pump, the static head on the hydraulic turbine and the water level in the source of cooling water supply.

2

More specifically, the present invention embodies means of maintaining, by suitable control means, any static head upon the hydraulic turbine, within the range determined by the depth of the penstock, so that under varying conditions of river level the maximum possible load can be thrown upon the turbine driven pump, thereby putting the minimum possible load upon the motor driven pump and thus keeping the power consumption of the motor driven pump at the lowest possible point under all conditions of varying river level.

With these and other objects in view, as may appear from the accompanying specification, the invention consists of various features of construction and combination of parts, which will be first described in connection with the accompanying drawing, showing a condenser circulating system of the preferred form embodying the invention, and the features forming the invention will be specifically pointed out in the claims.

In the drawing:

Figure 1 is a diagrammatic view of a system employing the present invention.

Figure 2 is a view on the line 2—2 of Figure 1 showing the turbine and the adjustable inlet gates associated therewith.

Referring more particularly to the drawing, 1 indicates a surface condenser of any approved type such as is employed in a power plant for condensing steam and through which condenser cooling water is circulated for condensing the steam therein. The cooling water enters the condenser through the inlet pipe 2 and leaves it through the outlet pipe 3.

The cooling water is taken from any suitable supply source (not shown) through the channel 4, and is picked up by the primary motor driven pump 5, from which it is discharged through the discharge pipe 6 into the suction of the secondary or booster pump 7. The secondary or booster pump 7 discharges the water through suitable piping 8 into the inlet piping 2 of the surface condenser 1.

A by-pass 9 is provided in which a check valve 10 is situated so that when the valve 11 in the discharge piping 6 to the suction of the booster pump 7 and the valve 12 in the pipe 8 are closed, the discharge from the primary pump 5 will pass directly into the by-pass 9 and into the inlet pipe 2, cutting out the booster pump 7.

The booster pump 7 is of any approved type of centrifugal pump adapted for the service, and includes an impeller (not shown) which is driven by the driving shaft 14. The driving shaft 14 is

connected by means of a coupling 15 to the driven shaft 16 of a hydraulic turbine 17, so that the booster pump 7 will be driven by the hydraulic turbine 17.

The primary pump 5 is driven by an electric motor or other suitable prime mover, as indicated at 18, and both this prime mover 18 and the condenser 1 are placed at relatively high elevations above the water channel 4 and the discharge water channel 19, into which the turbine 17 discharges. This places these elements of the power plant (not shown) either above a high water level in geographical locations where flood conditions are met with, or permits locations of these elements on a bluff or elevation above the water supply, when conditions are such as to make this type of installation practical and desirable.

The primary pump 5 may be of any approved type of construction of water circulating pump having a head capacity characteristic of sufficient rise to circulate some water through the circulating system and condenser upon starting of the apparatus and before the secondary or booster pump 7 comes into operation. The driver may be of constant or variable speed type, depending upon conditions of service to be met.

The secondary or booster pump 7 is of any approved type of centrifugal pump having the necessary and desired characteristics for performing its particular duties, and it has the same capacity in gallons per minute as the primary pump 5, its function being to boost the total dynamic head to that required by the water circulating system.

The hydraulic turbine 17 is driven by the water in the circulating system after it leaves the condenser 1. The outlet pipe 3 of the condenser 1 discharges into a control well or penstock 20, which latter has a pipe 21 connected to its lowermost portion. The pipe 21 delivers the circulating water to the inlet of the hydraulic turbine 17, and the operation of the hydraulic turbine 17 is controlled by means of the adjustable inlet gates 22, which are of the usual type of construction employed in hydraulic turbines.

The gates 22 are adjusted or shifted by a shifting rod 23, which is in turn connected by suitable linkage, as indicated at 24, with a float mechanism 25. The float mechanism 25 is positioned in the control well 20, and rises or falls with variation of the water level in the control well, thereby controlling the position of the inlet gates 22 of the hydraulic turbine 17 in accordance with variations in the quantity of water within the control well 20.

The control well or penstock 20 has an auxiliary outlet 26 therein located at a predetermined position above the bottom of the well. The auxiliary outlet 26 is normally closed by a sluice gate or other suitable type of valve, as indicated at 27. The sluice gate or valve 27 is opened when the hydraulic turbine 17 is cut out of the circulating system, either through the closing of the valves 11 and 12, or by the closing of the valve 28, which is positioned in the pipe 21 between the control well or penstock 20 and the turbine inlet. When the sluice gate 27 is open, the water flows from the control well 20 into a weir box 29, from which the water overflows to any suitable point of disposal. The weir 29 serves to maintain a minimum water level for sealing purposes in the control well or penstock 20.

When starting up the circulating system, the valves 11 and 12 are preferably closed, and the primary pump 5 assumes the responsibility or duty of supplying the cooling water to the con-

denser 1. When the line to the condenser 1 is filled, and the condenser itself is filled with the cooling water, the cooling water flows into the pipe 3 and thus into the control well 20, filling the control well or penstock 20 to a point or level at which the gates 22 of the turbine 17 are opened by float mechanism 25 and with valve 28 open the turbine 17 will operate. This causes the pump 7 to generate additional pressure in the pipe 3 which will close check valve 19, causing the discharge of the pump 5 to flow into the inlet of pump 7 and add to the total head produced.

The point of ultimate capacity is reached when the quantity and head produced by the pump 5 plus that produced by the booster pump 7 overcomes the frictional losses in the system plus the head required by the hydraulic turbine 17. Rise in the level of water in the source of supply (not shown) will decrease the head available on the turbine 17 but increase the discharge pressure of the pump 5 by a like amount. This action continues until the head on the turbine 17 has reduced sufficiently to make it unable to pass the full quantity of water available even with the gates 22 wide open. Under such conditions some of the water will be forced to spill at the weir 29.

When the level of water in the source of supply has risen to a point where the turbine power is insufficient to drive the booster pump 7 fast enough to develop any head the turbine 17 is cut out of the system during the circulation of cooling water through the system, the auxiliary outlet 26 is opened, causing the water level in the well 20 to fall by allowing the water to flow out of the control well into the weir box 29. At such times the weir box may be utilized to determine the discharge capacity of the motor driven primary pump 5.

While in the drawing and in the foregoing description the primary pump 5 and the booster pump 7 are shown as connected in series, it is to be understood that the present invention may also be employed in a system having the primary and booster pumps connected in parallel, such as is shown in Figure 2 of our companion application, filed August 19, 1941, Serial No. 407,446, without departing from the spirit of the present invention.

It will be understood that the invention is not to be limited to the specific construction or arrangement of parts shown, but that they may be widely modified within the invention defined by the claims.

What is claimed is:

1. In a power plant, the combination with a source of cooling water supply, of a surface condenser, a circuit for cooling water for said condenser, a primary pump in said circuit, a secondary pump in said circuit and having its inlet connected to the discharge of the primary pump, a turbine in said circuit driven by water flowing away from the condenser, said secondary pump connected to said turbine for operation thereby, and means for controlling the total static head on the inlet of said hydraulic turbine under variations in the water level in said source of supply.
2. In a power plant, the combination with a source of cooling water supply, of a surface condenser, a circuit for cooling water for said condenser, a primary pump in said circuit, a secondary pump in said circuit, a turbine in said circuit driven by water flowing away from the condenser, said secondary pump being connected

to said turbine for operation thereby, and a control well in the line between the outlet of the condenser and the inlet of the turbine to maintain the static head on the inlet of the turbine approximately constant under variations in the water level in said source of supply.

3. In a power plant, the combination with a source of cooling water supply, of a surface condenser, a circuit for cooling water for said condenser, a primary pump in said circuit, a secondary pump in said circuit, a hydraulic turbine in said circuit driven by water flowing away from the condenser, said secondary pump being connected to said turbine for operation thereby, a valved by-pass in said circuit constructed and arranged to permit said hydraulic turbine to be cut out of the circulating systems, means for maintaining the static head on the inlet of said turbine approximately constant under variations in the water level in the source of supply, and means for rendering said static head maintaining means ineffective when said turbine is cut out of the circulating system.

4. In a power plant, the combination with a source of supply of cooling water, of a surface condenser, a circuit for cooling water for said condenser, a primary pump in said circuit, a secondary pump in said circuit, a hydraulic turbine in said circuit driven by water flowing away from the condenser, said secondary pump being connected to said turbine for operation thereby, a valved by-pass in said circuit constructed and arranged to permit said hydraulic turbine to be cut out of the circulating system, a control well in the line between the outlet of the condenser and the inlet of the turbine, means actuated by the level of water in said well to control the static head on the inlet of the turbine under variations in the water level in said supply source, and means for lowering the water level in said control well to a level ineffective to control the static head on the turbine.

5. In a power plant, the combination with a source of supply of cooling water, of a surface condenser, a circuit for cooling water for said condenser, a primary pump in said circuit, a secondary pump in said circuit, a turbine in said circuit driven by water flowing away from the condenser, said secondary pump being connected to said turbine for operation thereby, a control well in the line between the outlet of the condenser and the inlet of the turbine, said turbine embodying inlet control gates, and means operated by variation in the water lever in the control well for operating said gates.

6. In a power plant, the combination with a supply source of cooling water, of a surface condenser, a circuit for cooling water for said condenser, a primary pump in said circuit, a secondary pump in said circuit, a hydraulic turbine in said circuit driven by water flowing away from the condenser, said secondary pump being connected to said turbine for operation thereby, a valved by-pass in said circuit constructed and arranged to permit said hydraulic turbine to be cut out of the circulating system, a control well in the line between the outlet of the condenser and the inlet of the turbine, means for lowering the water level in said control well, said turbine embodying inlet control gates, and means operated by variation in the water level in the control well for operating said gates.

7. In a power plant, the combination with a condenser, of a circuit for cooling water for said condenser, a primary pump including an impeller

in said circuit for circulating cooling water to said condenser, a secondary pump having an impeller in said circuit, a turbine in said circuit operatively connected with said secondary pump and driven by water flowing from said condenser to aid said primary pump in circulating water to said condenser, means for cutting said secondary pump and said turbine out of said circuit to cause said primary pump alone to circulate cooling water to said condenser, and means for discharging cooling water from said circuit at a point between the condenser and said turbine and so constructed and arranged as to maintain the circuit sealed with respect to the atmosphere at the point of discharge.

8. In a power plant, the combination with a surface condenser, of a circuit for cooling water for said condenser, a primary pump including an impeller in said circuit for circulating cooling water to said condenser, a secondary pump having an impeller in said circuit and having its inlet connected with the discharge of said primary pump, a turbine in said circuit operatively connected with said secondary pump and driven by water flowing from said condenser to aid said primary pump in circulating water to said condenser, and a valved by-pass for cutting said secondary pump out of said circuit.

9. In a power plant, the combination with a surface condenser, of a circuit for cooling water for said condenser, a primary pump including an impeller in said circuit for circulating cooling water to said condenser, a secondary pump having an impeller in said circuit and having its inlet connected with the discharge of said primary pump, a turbine in said circuit operatively connected with said secondary pump and driven by water flowing from said condenser to aid said primary pump in circulating water to said condenser, and a valved by-pass for cutting said turbine out of said circuit.

10. In a power plant, the combination with a surface condenser, of a circuit for cooling water for said condenser, a primary pump including an impeller in said circuit for circulating cooling water to said condenser, a secondary pump having an impeller in said circuit and having its inlet connected with the discharge of said primary pump, a turbine in said circuit operatively connected with said secondary pump and driven by water flowing from said condenser to aid said primary pump in circulating water to said condenser, and a valved by-pass for cutting said secondary pump and the turbine out of said circuit.

11. In a power plant, the combination with a surface condenser, of a circuit for cooling water for said condenser, a primary pump including an impeller in said circuit for circulating cooling water to said condenser, a secondary pump having an impeller in said circuit, a turbine in said circuit operatively connected with said secondary pump and driven by water flowing from said condenser to aid said primary pump in circulating water to said condenser, said turbine having inlet control gates, a well interposed in said circuit on the discharge side of said condenser, and means responsive to variations in the level of cooling water in said well for adjusting said gates in accordance with the level of the cooling water in the well.

12. In a power plant, the combination with a surface condenser, of a circuit for cooling water from said condenser, a primary pump including an impeller in said circuit for circulating cool-

ing water to said condenser, a secondary pump having an impeller in said circuit, a turbine in said circuit operatively connected with said secondary pump and driven by water flowing from said condenser to aid the primary pump in circulating water to said condenser, said turbine having inlet control gates, a well interposed in said circuit on the discharge side of said condenser, and means responsive to variations in the level of cooling water in said well for open-

5

10

ing and closing said gates in accordance with rising and lowering levels, respectively, of the cooling water in the well, said well being provided with a cooling water discharge so constructed and arranged as to maintain the circuit sealed with respect to the atmosphere regardless of the cooling water level in the well.
